UNITED STATES PATENT OFFICE.

JAMES C. FRENCH, OF MUSKEGON, MICHIGAN, ASSIGNOR TO AUSTIN MACHINERY CORPORATION, OF CHICAGO, ILLINOIS. A CORPORATION OF ILLINOIS.

ELONGATED CUBE MIXER.

Application filed January 8, 1921. Serial No. 434,644.

To all whom it may concern:

Be it known that I, JAMES C. FRENCH, a citizen of the United States, residing in Muskegon, in the county of Muskegon and 5 State of Michigan, have invented a new and useful Improvement in Elongated Cube Mixers, of which the following is a specification.

This invention relates in general to mixers for concrete and the like, and has more 10 particular reference to mixtures of polyhedral form.

A principal object of the invention is the provision of a mixer adapted to expedite the mixing operation, and at the same time to 15 insure intimate and proper mixing or intermingling of the material forming the batch.

My invention contemplates, in this regard, a movement producing rapidly recurring interfolding of the parts of the batch alternately from opposite directions as an incident 20 to the revolving of the mixer body or drum.

My invention contemplates also the accomplishment of those and other improvements 25 in the action in mixing without requiring the provision of additional delicate and complicated parts and without appreciably increasing the cost of the construction of the mixer.

Numerous other objects and advantages 30 of the invention will be apparent as it is better understood from the following description, which considered in connection with the accompanying drawings, illustrates

35 a preferred embodiment thereof.

Referring to the drawings,

Figure 1 is a side elevation of a mixer body or drum embodying my present invention;

40 Figs. 2 and 3 are end views thereof.

For the purpose of illustrating my invention I have shown on the drawing a mixer body or drum in which it is embodied, the frame of the apparatus being indicated 45 schematically in dotted lines. Since the mounting, operating means and other attendant parts form no part of my present invention, a particular description of them is not thought necessary to an understanding 50 of the invention. It may, however, be well to state that the mixer body is caused to rotate in action by the gear 11 mounted upon one of its ends and a driving pinion 12 suitably driven from the main power mechanism.

The mixer shown on the drawing, and for the purpose of illustrating my invention, is of new and improved shape or form. It is believed that this shape or form may be called an elongated cube. That is to say, 60 the construction is as it would be were a cube provided and mounted to rotate about a diagonal axis, and the faces converging at one side of said axis separated an even distance from the faces converged at the 65 other side of said axis, and spacing or connecting plates provided to connect the ends of the mixer thus separated.

In this connection, viewing Fig. 2, the axis is indicated at the point *a*, and the 70 three-end faces 13 are the three converging faces at one side. The corners or apexes of the cube at the axis are cut away to provide filling and discharge openings 14 and 15 so that the faces 13 at one side do not actually meet at the axis. The theoretical junction point, however, is indicated at *b* in 75 Fig. 1. The faces 16 in Fig. 3 are the three converging faces at the opposite end of the axis *a*.

Turning to Fig. 1, it will be noted that each face 13 at one side is spaced from the face 16 at the other side, with which it would connect were a mere cube employed by a spacing plate or wall 17. This construction results in a continuous series of 80 side walls indicated at 17, 18, and 19, arranged in zig-zag fashion, and each of parallelogrammatic shape.

Corner covers or reinforces 21 may be provided at the exposed corners if desired. Material is inserted through the opening 14, and during the rotation in the mixing action each flat side 17, 18, and 19 moves about the axis *a* and assumes a horizontal position 85 in passing the bottom. At this point, a certain amount of the batch rests upon it. As it moves up from the bottom it carries the material with it, folding it obliquely as it registers upper position. The next succeeding flat face or side wall acts similarly, but the material falls in from the opposite direction so that there is a continuous and powerful interfolding action as the mixing proceeds.

It is thought that the invention and many of its attendant advantages will be understood from the foregoing description, and it will be apparent that various changes may be made in the form, construction and ar- 100 105 110

angement of the parts without departing from the spirit and scope of the invention or sacrificing all of its material advantages, the form hereinbefore described being merely a preferred embodiment thereof.

I claim:

1. A polyhedric mixer body, having ends of truncated cubic form arranged with a horizontal axis extending through the theoretical projected cube corners, and intermediate connecting sheets or side walls spacing apart the companion edges of said ends of cubic form.
2. A polyhedric mixer body, including side plates or walls movable about the axis of the mixer, and having a horizontal position at the bottom, said side walls extending in a continuous series about the mixer in zig-zag fashion to provide recurring and oppositely acting interfolding of the batch in mixing.
3. A polyhedric mixer body, comprising wall parts arrangeable in general cubic form, and spacing members arranged between edges of said wall parts which would be joined to form a cube and lengthening the cube uniformly upon its axis, said body being supported to revolve about an axis extending through the corners of the supposed cube.
4. A polyhedric mixer body, comprising

wall parts arrangeable in general cubic form, and flat spacing members arranged between edges of said wall parts which would be joined to form a cube, said members being movable about the axis of rotation of the mixer and having a horizontal bottom position and an angular upper position.

5. A polyhedric mixer body, comprising oppositely converging wall members, and spacing members disposed between and connecting said wall members, said spacing members extending continuously around the mixer body in zig-zag relationship and being adapted to produce mixing action by directing portions of the mixture successively onto the batch in opposite directions.

6. A polyhedric mixer body, comprising wall parts arrangeable in general cubic form and said wall parts having elongated lateral edges therebetween and rotatable about a horizontal axis in the action of the mixer.

7. A polyhedric mixer body, supported for rotation about a horizontal axis extending through the corners of the body, said body having intermediate parts uniformly spacing the sides of the body apart to lengthen the body upon its axis and to form successively acting mixing elements.

JAMES C. FRENCH.
